(57) **CLAIM**

The ornamental design for a pad for the jaws of a clamp, as shown and described.

DESCRIPTION

FIG. 1 is a front, top side perspective view of a pad for the jaws of a clamp showing my new design;

FIG. 2 is a front, bottom side perspective view thereof;

FIG. 3 is a rear, top side perspective view thereof;

FIG. 4 is a rear elevation view thereof;

FIG. 5 is a front elevation view thereof;

FIG. 6 is a left side elevation view thereof, with the right side elevation view being a mirror image;

FIG. 7 is a top plan view thereof; and,

FIG. 8 is a bottom plan view thereof.

The broken lines in the drawings depict portions of the pad for the jaws of a clamp that form no part of the claimed design.
